UNITED STATES PATENT OFFICE.

MARY H. HANNAH, OF CHICAGO, ILLINOIS.

MEANS FOR FASTENING RUGS ON CARPETS.

1,312,323.

Specification of Letters Patent. Patented Aug. 5, 1919.

Application filed October 11, 1918. Serial No. 257,682.

To all whom it may concern:

Be it known that I, MARY H. HANNAH, a citizen of the United States of America, and a resident of Chicago, Illinois, have invented 5 a certain new and useful Improvement in Means for Fastening Rugs on Carpets, of which the following is a specification.

This invention contemplates means for the securing in place of rugs on carpets, so 10 that the rugs will not shift around or creep over the surface of the carpet, and whereby the edges of the rugs will be held firmly in place.

It also contemplates a novel form of fastening device which can be inserted through 15 the rug and into the carpet, near the edge of the rug, and then held in place by the edge of the rug itself.

To these and other useful ends the invention 20 consists in matters hereinafter set forth and claimed.

In the accompanying drawings—

Figure 1 is a perspective of a carpet having 25 a rug fastened thereon in accordance with the principles of the invention.

Fig. 2 is an enlarged detail sectional view, showing the method of inserting the fastening device through the rug and into the carpet.

Fig. 3 is a perspective of one of the fastening devices.

As thus illustrated, the fastening device comprises a straight length of wire 1 having 30 a point 2 at one end and a head 3 at its other end. It will be seen that said head is hook-shaped, being U-shaped in form, and that one side of the head is in alinement with the straight length of wire. In this way the prong 4 of the hook extends parallel with 35 the straight length of wire, for a short distance, and is connected to the other side of the head by the curved portion 5, so that the head is U-shaped with one side thereof extended in a straight line to form a relatively 40 long portion which is pointed at its end.

The method of using the fastening device 45 is as follows: The rug is laid on the carpet, in the desired position, and fasteners are then applied to the edges thereof. As shown 50 in Fig. 2, each fastener is inserted downwardly and slantingly through the rug, adjacent to the edge thereof, and through the carpet until the head is over the edge of the rug. The fastener is then turned to bring 55 the prong 4 of the hook-shaped head in position to be brought under the edge of the

rug by the final insertion of the fastener into the rug and carpet. In this way, each fastener is held against turning around in the rug and carpet, and is prevented from being inserted beyond a certain point. The head of the fastener is very nearly concealed at the edge of the rug, so that it is not noticeable, and in addition it is so formed that the fastener is not liable to be kicked out or 60 dislodged by the feet of those walking across the carpet and rug. In other words, there is nothing which protrudes far enough to catch the feet, and even when stepped on the fasteners are not liable to be broken or 65 distorted. When the foot of a person rests on the fastener, it tends to turn over sidewise in an effort to rest flatwise upon the carpet, and this causes it to bind more tightly in the rug, and to more effectively resist withdrawal from the rug and carpet. The points 70 of the fasteners cannot do any harm, as they can never be turned upward and will always be below the carpet. As many of these fasteners can be applied around the edges of the 75 rug as may be desired, as shown in Fig. 1, in a manner that will be readily understood.

The fasteners can be made in different sizes, for rugs of different thicknesses, and they can be made of steel or any other suitable metal, and can be formed from short 80 lengths of wire.

With the construction shown and described, the fastening device comprises two sides or ends which are of unequal length, 85 one end extending much farther within the double thickness provided by the rug or carpet than the other or shorter end. However, both ends are insertible successively endwise, the long portion into said double 90 thickness and the short portion under the edge of the rug, in the manner shown and described, and with the result that the rug is effectively fastened to the carpet by a device which is not only easily inserted, but also 95 easily withdrawn when such is desired. At the same time, though, as explained, the device is not liable to be bent or distorted by the feet, is held by the edge of the rug against twisting out of place, and is not 100 liable to be kicked out or dislodged after being once properly inserted.

What I claim as my invention is—

The combination of a floor, a carpet on 110 said floor, a rug laid thereon, with the carpet extending beyond the edge of the rug, and retaining means in the form of a fas-

- tener having a single long sharp pointed portion extending inwardly and downwardly at an angle through the carpet and rug, so that the sharp point is below the surface of the carpet, and whereby practically this entire portion is embedded in the fabric of the rug and carpet, a curved portion extending snugly over and around said edge from the outer end of said long portion, and
5 10 a much shorter portion extending inwardly under said edge from said curved portion

Copies of this patent may be obtained for five cents each, by addressing the "Commissioner of Patents.

Washington, D. C."

to form a head that limits the straight end-wise insertion of the fastener and which is held by the edge of the rug against twisting around, the two portions of unequal length being respectively insertible successively into the double thickness formed by the rug and carpet and under the edge of the rug, and the fastener being removable by a straight pull on the head thereof.

MARY H. HANNAH.
